JOHN MATTHEWS, JR., OF NEW YORK, N. Y.

Letters Patent No. 98,176, dated December 21, 1869.

IMPROVEMENT IN APPARATUS FOR DISPENSING SODA-WATER SIRUPS.

The Schedule referred to in these Letters Patent and making part of the same.

To all whom it may concern:

Be it known that I, JOHN MATTHEWS, Jr., of the city, county, and State of New York, have invented a new and useful Improvement in Apparatus for Dispensing Soda-Water and Sirups, of which the following is a full, clear, and exact description, reference being had to the accompanying drawing, forming part of this specification, and in which—

Figure 1 represents a sectional elevation of an apparatus, in part, for dispensing soda-water and sirups, having my invention applied to it, and

Figure 2, a sectional plan taken as denoted by the line *xx* in fig. 1.

Similar letters of reference indicate corresponding parts.

My invention consists in a novel arrangement, within the box or case which contains the soda-water cooler, and so that they lie below said cooler, of the sirup-cans or vessels of the apparatus; also, a certain arrangement, relatively to the sirup-cans or vessels, of an opening or openings in the back of the case, to provide for filling of said cans or vessels, in combination with a swinging or pendent, and automatically-closing lid or door to such opening or openings.

Furthermore, the invention includes a novel construction of the sirup-cans or vessels, and whereby, on suitable pressure being applied, they are made to tilt or tip to discharge the sirup through their forward ends, which are of spout-like form, and afterward caused to adjust themselves to their original or non-discharging position; and in this connection the invention comprises a front lever-like extension to the sirup-cans, constructed to form a guard to the tumbler, to prevent its withdrawal from under the spout of the can, while the latter is discharging sirup, and which may serve as a means for tilting the can, said extension or guard preferably being of an elastic character, and operating in connection with a stationary tumbler-guide below, and with stops to regulate the action of the can, as hereinafter explained.

Referring to the accompanying drawing—

A represents the box or case, which contains the cooler *B*, that holds the ice or frigorific mixture, and has a worm, *C*, arranged in its bottom, through which the soda-water is passed from the fountain by a lower leg, *a*, and discharged, as drawn, by or through a front upper bend, *b*.

Connected with the bottom of the cooler, also, is the drain-pipe *c*, for running off water as formed in the cooler.

D is the top of the box or case, preferably fitted on a loose or detachable manner, and made to form double lids *d e*.

Arranged below the cooler *B*, within the box or case *A*, is any suitable number of sirup-cans or ves-

sels *E*, which are hung so as to rock on a cross-shaft, *f*, and preferably so that they may be lifted therefrom, and out of the box or case, when required.

These sirup-cans *E* are represented as of boat or trough-like form, and of greater weight or capacity at their ends, which lie back of the cross-shaft, and such heel or back portions of them formed with filling-openings *g* at their top; while their portions which lie on the other side of the supporting rock-shaft, and extend toward the front of the case, are of a spout-like shape.

These cans may be filled or replenished from time to time with sirups, through an opening made in the back portion of the case, arranged above and in rear of the open heel-portions of the cans, and fitted with a pendent or swinging door, *F*, that on being pressed inward, gives access to the filling-ends of the cans, but that on being released again, swings to close said opening and exclude dust and flies from the sirup.

The arrangement, however, of the sirup-cans below the cooler, and in proximity to it, forms, in itself, a protection against flies, and keeps the sirup always cool, and this without any additional cost, as regards frigorific mixture, beyond what is requisite to cool the soda-water, the cooler *B* not being made any deeper than necessary, and preferably sloping at its back to allow of the door *F* swinging, as described.

The bottom portion of the front of the case is also provided with a lid or door, *G*, that is turned up or opened, when working the apparatus, to allow of the introduction of a tumbler, *H*, or tumblers, up against a tumbler-guide, *I*, that directs said tumblers to their proper position for reception of sirup from the cans, when the latter are depressed at their forward-ends.

In their normal position, and when charged with sirups of different kinds, the cans or vessels *E* occupy the position represented for them by full lines in fig. 1, and may rest, at their heel-portions, on a stop, *h*, where they are retained by gravity, and prevented from discharging; but where any one of such cans is required to discharge a portion of its contents, according to the description of sirup needed, then said can is tilted or tipped, as represented by dotted lines in fig. 2, the quantity so discharged into the tumbler arranged below it being regulated by the degree of downward tip given to the forward end of the can.

As a convenient means for thus tilting or tipping the cans, each of them is or may be provided, at its front end, with a bent lever-like extension, *J*, that may carry a label, *i*, indicating the description of sirup or flavoring-mixture contained in the can, and on which the finger may be pressed to tilt the can, that resumes its original position on such pressure being removed.

This extension-piece *J*, also, by being bent downward, serves as a guard to prevent the tumbler from

being removed while the can remains in a discharging-position, and being of an elastic character, it is restrained from breaking or injuring the tumbler, if brought down sharply or heavily against it; also protects the sirup-cans or vessels, when made of glass, from being broken by contact with the tumblers.

Said guard may also serve as a spring to break shock, by striking the upper portion of the front of the case, at *k*, when the can is allowed to swing back to its original position; and furthermore, it operates, when the can is depressed, to prevent spitting out of the sirup beyond the tumbler.

An apparatus thus constructed or provided, affords many facilities and forms a rapid means for supplying sirups to soda-water on draught.

What is here claimed, and desired to be secured by Letters Patent, is—

1. The arrangement, in a soda-water apparatus, of the cooler *B*, the cooling-worm *C*, and the sirup-cans or vessels, entirely below the cooler, and within the box or case containing the latter, substantially as specified.

2. The arrangement of the door *F*, in the case *A* of a soda-water apparatus, with relation to the sirup-cans or vessels *E*, and hung to open inward over the filling-ends of said cans, as shown and described.

3. The sirup-cans or vessels, constructed of a boat or trough-like form, having openings at their tops in the rear, but of spout-shape in front, and hung so as to rock or tilt on suitable pressure being applied, with freedom to adjust themselves on such pressure being removed, essentially as herein set forth.

4. The combination, with the tilting sirup-cans or vessels, of tumbler-guards *J*, connected with or carried by said cans in front, substantially as and for the purpose or purposes herein set forth.

5. The combination of the stationary tumbler-guide *I* with the tumbler-guards *J*, for adjusting and holding the tumblers in place beneath the delivery-ends of the sirup-cans or vessels, essentially as specified.

JOHN MATTHEWS, JR.
